(57) **CLAIM**

The ornamental design for a voice controller as shown and described.

DESCRIPTION

FIG. 1 is a perspective view of a voice controller showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is the second perspective view showing the voice controller.

The broken lines shown in the figures are for the purpose of illustrating portions of the voice controller and form no part of the claimed design.
